Primary Examiner—T. Chase Nelson*Assistant Examiner*—David G Muller*(74) Attorney, Agent, or Firm*—Linda A. Fox(57) **CLAIM**

The ornamental design for an injection device, as shown and described.

DESCRIPTION

FIG. 1 is a perspective view of an injection device showing our new design.

FIG. 2 is a first side view thereof.

FIG. 3 is a second side view thereof.

FIG. 4 is a top view thereof.

FIG. 5 is a bottom view thereof.

FIG. 6 is a front view thereof; and,

FIG. 7 is a back view thereof.

The features shown in broken lines depict environmental subject matter only and form no part of the claimed design.
